UNITED STATES PATENT OFFICE

ALBERT STEINMANN, OF LA CHAUX-DE-FONDS, SWITZERLAND

ADDING MACHINE

Application filed October 29, 1930, Serial No. 492,012, and in Switzerland March 27, 1930.

The present invention relates to a particularly light, portable adding machine of relatively small dimensions, wherein the number to be added is set up by means of manually operable number slides, each of which, by means of a rack, actuates a totalling mechanism having rotatable counting disks. In such a machine, each rack, upon actuation of the slide, comes into engagement with a drive 5 constantly in mesh with a counting wheel of the totalling mechanism, and all of the said drives are mounted on a common slide, which on the other hand, controls ratchet wheels co-operating with the racks.

Known apparatus and machines of such type all possess the defect that the totalling operation can take place only after the drives with which the racks are engaged are disconnected. The result is that the number 20 thus set up, that is the number to be added, is no longer visible in the windows of the machines at the time that the sum of the calculating operation appears in the windows of the totalling mechanism, this difficulty resulting from the fact that at the moment at which the drives are disconnected by movement of the slide, the ratchets of the racks are also disconnected by the slide and the 25 number slide is returned to its initial position.

Applicant substantially eliminates this difficulty by insuring that the totalling mechanism can completely carry out the addition without any preceding operation, or in other words, in such manner that the transfer of 30 a number unit to the next highest number position of the totalling mechanism can proceed even if several, perhaps all of the racks of the counting slide are engaged with their corresponding drives, the result being that the number to be added or set up, and the sum 35 of the addition are simultaneously visible in the corresponding windows of the machine.

According to applicant's invention the machine is characterized by the provision of 40 drives on the common slide, which drives are journaled with each pin in a longitudinal guide opening of the slide, and are subjected to the action of a spring urging the return of 45 such slides to their zero or rest position. The

arrangement is such that all of the drives with their corresponding racks are positively and simultaneously removed from engagement when the slide is actuated, and so that each individual drive in engagement with a 55 rack, under the action of the corresponding counting wheel, automatically either describes a movement relative to the slide, or is disengaged with the rack when the corresponding counting wheel rotates as a result of 60 the transfer of a number unit to the next highest counting position of the totalling mechanism. To carry out the invention there is the necessary prerequisite that all of the 65 counting disks of the totalling mechanism rotate in the same direction under the actuation of the racks of the counting disks, or during the transfer of a number unit. However, this last mentioned feature does not 70 form part of the invention covered by the present application.

An object of my invention is to produce a new form of adding machine.

Another object is to produce an extremely 75 small and portable adding machine.

Another object is to produce a small portable adding machine of great strength.

Another object is to produce an adding machine having at least three rows of sight openings 80 through which the movable members of the mechanism may be viewed.

Another object is to produce a new form of 85 number slider, together with its cooperating parts, for use in an adding machine.

Another object is to produce a new form of transfer mechanism for an adding machine.

Another object is to produce a new arrangement of biasing springs.

Still another object is to produce a new form of rack and pinion mechanism for transferring values in an adding machine.

Yet another object is to produce a new 90 method of mounting a number slider in an adding machine.

Other objects and advantages will appear hereinafter.

In the drawings, in which is illustrated by 100

way of example one modification of my invention,

Figure 1 is a front view of the entire machine, a portion of the outer case being broken away,

Figure 2 is a longitudinal section on an enlarged scale of the carriage supporting the pinions controlled by the racks,

Figure 3 is a fragmentary elevation on an enlarged scale of a totalizer and its controlling members,

Figure 4 is a longitudinal section of the machine relative to the slide for guiding a number slider, while

Figure 5 is a section on the line V—V of Fig. 3, and illustrates the method of mounting two biasing springs on a single screw.

The machine in its preferred form comprises a case 15 formed by a rectangular frame and front and rear plates, these three members being assembled by any suitable means such as screws, not shown. The frame of the mechanism is fitted in the case 15, and this frame preferably comprises a plate 16 and two cross members 17 and 18 joined to the back of the plate 16 by means such as pillars 19. As shown, three rows of sight openings 20, 21, and 22 are formed in the case 15, the sight openings 20 comprising longitudinal slots opposite which are inscribed, in increasing sequence upwardly, the numerals "1" to "9", each corresponding to one of nine holes 24 formed in the number slider 23, one of which is arranged in the rear of each sight opening 20. The holes 24 permit the movable sliders 23 to slide downwardly when suitably actuated by means of a peg or rod introduced through the sight opening 20 into one of the holes 24. On each slider there is inscribed in increasing sequence upwardly the numerals "0" to "9", as shown at the right side of Fig. 1. These numerals, however, are removed with respect to those arranged opposite the sight openings 20, so that the numeral "0" is visible in the corresponding sight opening 21, at such times as the slider is in its rest position, at the top of its ascending path. The sliders of Fig. 1 are shown in such top position.

The sliders 23 are preferably mounted and movable on the cross member 17. To this end, each slider is assembled with a rigid bar 25 by means such as screws 27 and 28, and is mounted about a guideway or slot 26 formed in the cross member 17. Each screw 27 and 28 preferably carries a guide roller 29 adapted to roll along the said slide, to guide the slider and to limit the path thereof. The bar 25 terminates at its lower end in a rack portion 25' adapted to operate a pinion 30 connected to the totalizing mechanism. Suitable means are provided for the return of the slider to its normal position, and in the preferred instance such means takes the form of

a helical biasing spring 31, one end of which is connected to the screw 28, the other end being connected to means such as a screw 32 fixed to the plate 16.

A corresponding pawl 33 cooperates by means of its projection with each of the said racks, the pawl being pivoted at 34 about the plate 16, and being normally forced into engagement with the said rack by means such as a biasing spring 35.

The pinions 30 are preferably mounted in a carriage 36, best shown in Figs. 1 and 2, which carriage is shown as being fitted on the cross member 18 by means such as a screw 37 extending through elongated holes 38 of the carriage, whereby the latter is adapted for slight reciprocating motion transversely to the movement of the racks 25'. Means such as a button 39 are provided for manual operation of the said carriage. The pinions 30 are shown as provided with pivots and as being mounted on the carriage thereby, each of the said pivots preferably being housed in an elongated opening 40 in the carriage. This construction permits movement of the pinion relative to the carriage and to the corresponding rack 25'. The pinion is normally maintained in engagement with the corresponding rack by suitable means such as a biasing spring 41, and any movement of the pinion in the elongated hole or recess 40 takes place against the tension of the said spring. The pinion 30 is thus adapted for slight movement away from the rack 25' for disengagement therefrom.

Each of the said pawls 33 engages by means of its projection in a notch 42 of the carriage 36, so that upon movement of the latter, all of the pawls are compelled to pivot against the tension of their respective biasing springs 35, and to be disengaged from the corresponding rack 25'. This action takes place whenever the carriage is moved to the right as shown in Figures 1 and 2, by means of the button 39. At such times the pinions 30 also follow the movement of the carriage and are removed from the teeth of such rack against the tension of their respective biasing springs 41. The said last mentioned springs also serve the function of insuring the return of the carriage 36 to its rest position after the button 39 has been released, through the intermediary of the pinions 30.

Each of the pinions 30 is shown as engaging, regardless of its relative position with respect to the rack 25', with a counting wheel 43, of the totalizing mechanism.

In the preferred form of the invention the biasing springs 35 and 41 of any given pinion 30 and pawl 33 are fixed together on a small bar 45 by means such as a single screw 44, which latter joins the bar 45 to the plate 16, as best shown in Figures 3 and 5. For this purpose, the small bar 45 is provided

with a boss 46 pierced with a round hole. A socket 47 is lodged in the bottom of the said hole and bears against the plate 16. The spring 35 engages between the bearing of the socket and the plate 16 by means of a portion 35' curved to form a semi-circle. The straight flexible projection of the said spring is preferably disposed in a corresponding reamed channel 46' of the boss of the small bar, as shown in Figure 3. The spring 41, one end of which is of the same semi-circular configuration as the corresponding end of the spring 35, is secured by the said similar portion between the socket 47 and the head of the screw 44 at such times when the latter is screwed tightly into the plate 16. The straight flexible extremity of the spring 41 also extends through the reamed channel 46' and the boss 46.

Each counting wheel 43 is preferably keyed on a shaft 48, on which are also keyed a numeral disc 49 placed behind the corresponding sight opening 22, a star wheel 50 engaging with a detent 51 fixed to a small bar 52 by means such as a screw 53, a finger 54, and a toothed wheel 55 engaging with a gear 56. The arrangement of the several parts just referred to are perhaps best shown in Figures 3 and 4. The star wheel, the wheel 55, and the gear 56 have ten teeth each, the disc 49 bearing the numerals "0" to "9", one of which is always visible through the corresponding sight opening 22. The star wheel 50 through its cooperation with the detent 51 insures the maintenance of the requisite position of the corresponding shaft 48 and the members carried thereon.

Treating more particularly of the finger 54, it is to be kept in mind that its function is, through the medium of the gears 56 mounted on the plate 16, to transfer the tens of a unit of a low order, to the unit of the next higher order.

It is obvious that the totalizing mechanism must have means for resetting it to zero. The means provided in the present instance are preferably controlled by a button 58, and the means employed are based on a very novel idea. Such means constitutes the subject matter of applicant's copending application Serial No. 492,013 filed concurrently herewith. Since it is obvious that such zero-resetting means may take the form of any of the large number of conventional forms of construction, the particular form of such means does not come within the scope of the present invention and is not disclosed in detail in this application.

The operation of the machine described in the foregoing disclosure is as follows:—

The sliders 23 represent both the single and compound units of the decimal system of calculation, as ordered in the conventional right to left-hand direction in Figure 1, that is, the single units, tens, hundreds, etc. For

example, in order to add the numbers 75 and 83, the two first sliders 23 are operated, the number 75 being first set up. For this purpose, the peg or rod is introduced in the hole placed opposite the number 5 of the first slider, and the latter is then caused to slide downward until the rod bears against the end of the sight opening 20. This operation is repeated on the said second slider by introducing the rod in the hole opposite the number 7. The number 75 is then visible in the two right-hand sight openings 21 and in the two right-hand openings 22 of the totalizer. By actuating one of the sliders as described above, its rack 25' engages with its corresponding pinion 30 and entrains the same; this pinion in its turn entrains the corresponding counting wheel 43 as well as the aforementioned members keyed on the shaft 48 of the counting wheel, and rotates the same through an angular movement proportional to the linear movement of the said slider. When the slider is at the end of its path, it is prevented from returning to its normal position under the actuation of the spring 31 by means of the pawl 33, which engages by means of its projection in the rack 25'.

When the number 75 has been set, it is necessary to return the two displaced sliders to their original position before the next number can be set up. The return to zero of the sliders is effected by means of the carriage 36 which is moved to the right by the button 39 so that the pinions 30 and the pawls 33 are spaced apart from the racks 25'. This movement is permitted by the limited motion of the carriage 36 relative to the cross member 18 through a space determined by the travel of the holes 38 relative to the screws 37 arranged therein. Such movement carries the pinions 30 against the action of the corresponding springs 41, and pivots the pawls 33 against the action of the corresponding springs 35. The racks 25' are then returned, together with the sliders 23, to their original position under the urging of their corresponding biasing springs 31. The same action takes place in connection with the carriage 36, which resumes its original position under the actuation of the springs 41 immediately after the button 39 has been released.

The foregoing operations are repeated for effecting the addition of the number 83. This number is then readable in the two right-hand sight openings 21, while at the same time the totalizer has the reading 158, readable in the three right-hand sight openings 22, and which forms the sum of the two numbers which have been added.

In the preferred instance the transfer of the tens of the totalizing mechanism is effected by the finger 54 which during each revolution advances through the intermediary of 130

the gear 56, the toothed wheel 55 of the unit of the next higher number, to the extent of one tooth. The counting wheel 43 then rotates in the direction indicated by the arrow in Fig. 3, whereby the corresponding pinion 30, which engages with the wheel 43, is shifted to the right relative to the elongated holes 40. The pinion 30 is thus disengaged from the rack 25', thus insuring the transfer. 10 Immediately after the action of transfer, the pinion 30 is reengaged with the corresponding rack under the action of the biasing spring 41.

It is obvious that the invention is susceptible to numerous modifications without departing from the spirit of the invention, and it is intended that the invention be limited only by the scope of the appended claims. 15

What I claim is:

20 1. In an adding machine, comprising a frame, and a totalizing machine consisting of a plurality of counting disks, and a plurality of pinions for actuating them; means for setting said pinions, comprising a plurality of rectilinearly movable rack bars, means normally urging said rack bars into their zero position, means for normally locking the rack bars in any position thereof other than zero, and in which position the 25 rack bars engage with and actuate said pinions, and means for disengaging said rack bars and pinions, and said locking means whereby the rack bars can be restored to their zero position.

30 35 2. In an adding machine, comprising a frame, and a totalizing machine consisting of a plurality of counting disks, and a plurality of pinions for actuating them, means for setting said pinions, comprising a plurality of rectilinearly movable rack bars, means normally urging said rack bars into their zero position, spring-biased means for normally locking the rack bars in any position thereof other than zero, and in which 40 position the rack bars engage with and actuate said pinions, and means for disengaging said rack bars and pinions, and said locking means, whereby the rack bars can be restored to their zero position.

45 50 3. In an adding machine, comprising a frame, and a totalizing machine consisting of a plurality of counting disks, and a plurality of pinions for actuating them; means for setting said pinions, comprising a plurality of rectilinearly movable rack bars, means normally urging said rack bars into their zero position, spring-biased pawls for normally locking the rack bars in any position thereof other than zero, 55 and in which position the rack bars engage with and actuate said pinions, and means for disengaging said rack bars and pinions, and said pawl, whereby the rack bars can be restored to their zero position.

55 4. In an adding machine, comprising a

frame, and a totalizing machine consisting of a plurality of counting disks, and a plurality of pinions for actuating them; means for setting said pinions, comprising a plurality of rectilinearly movable rack bars, means normally urging said rack bars into their zero position, spring-biased pawls for normally locking the rack bars in any position thereof other than zero, and in which position the rack bars engage with and actuate said pinions, means for normally urging said pinions against said rack bars, and means for disengaging said rack bars and pinions, and said pawls, whereby the rack bars can be restored to their zero position. 70

5. In an adding machine, comprising a frame, and a totalizing machine consisting of a plurality of counting disks, and a plurality of pinions for actuating them; means for setting said pinions, comprising a plurality of rectilinearly movable rack bars, means normally urging said rack bars into their zero position, spring-biased pawls for normally locking the rack bars in any position thereof other than zero, and in which position the rack bars engage with and actuate said pinions, resilient means for normally urging said pinions against said rack bars, and means for disengaging said rack bars and pinions, and said pawls, whereby the rack bars can be restored to their zero position. 80

6. In an adding machine, comprising a frame, and a totalizing machine consisting of a plurality of counting disks, and a plurality of pinions for actuating them; means for setting said pinions, comprising a plurality of rectilinearly movable rack bars, means normally urging said rack bars into their zero position, spring-biased pawls for normally locking the rack bars in any position thereof other than zero, and in which position the rack bars engage with and actuate said pinions, spring-biased means normally urging the said pinions against said rack bars, the springs biasing each pawl and the pinion corresponding to the rack with which said pawl is adapted to engage being mounted at a common point, and means for disengaging said rack bars and pinions, and said pawls, whereby the rack bars can be restored to their zero position. 90

7. In an adding machine, comprising a frame and a totalizing machine consisting of a plurality of counting disks, and a plurality of pinions for actuating them; means for setting said pinions, comprising a plurality of rectilinearly movable rack bars, means normally urging said rack bars into their zero position, spring-biased pawls for normally locking the rack bars in any position thereof other than zero, and in which position the rack bars engage with and actuate said pinions, spring-biased means normally urging the said pinions against said rack bars, and a carriage adapted for limited movement and 100

adapted to carry said pinions and said pawls, against the action of their biasing means, out of contact with said rack bars, whereby the latter can be restored to their zero position.

8. In an adding machine, comprising a frame, and a totalizing machine consisting of a plurality of counting disks, and a plurality of pinions for actuating them; means for setting said pinions, comprising a plurality of rectilinearly movable rack bars, means normally urging said rack bars into their zero position, spring-biased pawls for normally locking the rack bars in any position thereof other than zero, and in which position the rack bars engage with and actuate said pinions, spring-biased means normally urging the said pinions against said rack bars, and a movable carriage adapted for limited movement and having a plurality of elongated pivot holes therein, in which the said pinions are mounted for limited linear movement relative to the carriage, manual operation of the carriage causing corresponding movement of the pinions and pawls for disengaging them from the racks, whereby the latter can be restored to their zero position.

9. In an adding machine, comprising a frame, a plate mounted in said frame, and a totalizing machine consisting of a plurality of counting disks, and a plurality of pinions for actuating them; means for setting said pinions, comprising a plurality of manually operable number sliders comprising parts on each side of the said plate, screws passing through the said plate and assembling the sliders, guide rollers mounted about at least some of the said screws, racks connected to each of the said sliders, and normally engaging with said pinions, means normally urging said racks into their zero position, means for normally locking said racks in any position other than zero, and in which locked position the racks engage with said pinions, and means for disengaging said racks and pinions, and said locking means, whereby the rack bars can be restored to their zero position.

10. In an adding machine comprising a frame, means movable in a substantially rectilinear direction along the line of the force imparted thereto as an incident to setting up numbers on the machine, and pinions cooperating with and normally engaging said means; a totalizing mechanism comprising a plurality of counting wheels engaged with and actuated by said pinions to register values transmitted to them by said pinions, means normally tending to prevent disengagement of said pinions from said first means, and means for disengaging said pinions and said first means, whereby additional values can be transferred to said totalizer.

11. In an adding machine having manually

operable member slides for setting up the number to be added, a totalizing mechanism having rotatable counting disks, racks on said slides for actuating said disks, and drives constantly engaging with corresponding counting wheels and which drives are contacted by corresponding racks upon actuation of the corresponding slides; means for resetting the slides, comprising a common slide in which the said drives are mounted, the said drives each having pins inserted in corresponding guide openings of the slide, whereby they are adapted for limited movement relative to said slide, resilient means for urging the drives into contact with the racks, the drives being positively and simultaneously disengaged from their corresponding racks upon actuation of the slide, and means for breaking the engagement between any particular rack and the corresponding drive when the corresponding number wheel rotates as the result of the transfer of the unit to the next highest counting position of the totalling mechanism.

12. In an adding machine having manually operable member slides for setting up the number to be added, a totalizing mechanism having rotatable counting disks, racks on said slides for actuating said disks, and drives constantly engaging with corresponding counting wheels and which drives are contacted by corresponding racks upon actuation of the corresponding slides; means for resetting the slides, comprising a common slide in which the said drives are mounted, the said drives each having pins inserted in corresponding guide openings of the slide, whereby they are adapted for limited movement relative to said slide, resilient means for urging the drives into contact with the racks and for returning the slide to its initial position, the drives being positively and simultaneously disengaged from their corresponding racks upon actuation of the slide, and means for breaking the engagement between any particular rack and the corresponding drive when the corresponding number wheel rotates as the result of the transfer of the unit to the next highest counting position of the totalling mechanism.

In testimony whereof I have signed my name to this specification.

ALBERT STEINMANN.
